UNITED STATES PATENT OFFICE

92,939

DESIGN FOR A COMBINED SPOOL HOLDER AND DISPENSER

Levite Albert, Northampton, Mass.

Application May 21, 1934, Serial No. 51,860

Term of patent 14 years

To all whom it may concern:

Be it known that I, LEVITE ALBERT, a citizen of the United States of America, residing at Northampton, in the county of Hampshire and State of Massachusetts, have invented a new, original, and ornamental Design for a Combined Spool Holder and Dispenser, of which the following is a specification, reference being had to the following drawing, forming a part thereof.

I claim:

The ornamental design for a combined spool holder and dispenser as shown.

LEVITE ALBERT.
